HINGE BUTT AND METHOD OF MAKING THE SAME

Filed Dec. 27, 1929

UNITED STATES PATENT OFFICE

JOSEPH SOSS, OF ROSELLE, NEW JERSEY

HINGE BUTT AND METHOD OF MAKING THE SAME

Application filed December 27, 1929. Serial No. 416,785.

This invention relates to hinges of what are known as the covered joint type and particularly to the method of making the butt of such a hinge which includes the hood for covering or concealing the joint of the hinge; and the object of the invention is to provide an improved and simplified method of manufacturing hinge butts of the class specified from a sheet metal blank wherein two identical butts are fashioned in one series of forming operations, thereby materially reducing the cost of manufacture, and further whereby the resulting products will be more accurately produced at a minimum waste in scrap material; a further object being to provide a novel method of forming a pair of hinge butts of identical construction wherein the hood portions of said butts are fashioned from the central portion of the blank in such manner as to equally distribute the distribution of the flow of metal in shaping the hood portions therefrom and prevent creeping or other displacement of the work-piece; and with these and other objects in view, the invention consists in a hinge of the class and for the purpose specified, made in accordance with the method more fully hereinafter described and claimed.

The invention is fully disclosed in the following specification, of which the accompanying drawings, form a part, in which the separate parts of my improvement are designated by suitable reference characters in each of the views, and in which:—

Fig. 1 is a longitudinal, sectional view through a hinge butt made according to my invention.

Fig. 2 is a face view of the butt shown in Fig. 1.

Fig. 3 is a plan view illustrating the general form of a blank from which a pair of hinge butts similar to that shown in Figs. 1 and 2, is formed.

Fig. 4 is a diagrammatic view of two die

parts illustrating the first step in forming the blank shown in Fig. 3.

Fig. 5 is a view similar to Fig. 4 but viewing the die from a position at right angles to that shown in said figure.

Fig. 6 is a diagrammatic view showing other die parts employed in completing the formation of the hoods on the pair of hinge butts.

Fig. 7 is a partial view of the dies illustrated in Fig. 6 as viewed from a position at right angles to that shown in said figure; and Fig. 8 is a sectional detail view similar to Fig. 1 showing only a part of the hinge butt and illustrating a modification.

My invention relates primarily to the formation of hinge butts constituting one butt part of a complete hinge and said butt part may include other members or parts in forming the complete butt. While this butt may be formed from relatively thin sheet metal in the preferred form of the construction and especially when used as a complete butt part, the same is fashioned from a comparatively heavy sheet of metal.

In Figs. 1 and 2 of the drawings, I have shown one of a pair of butts formed according to my improved method. In said figure, 10 represents the attaching plate portion of the butt which includes a plurality of screw receiving apertures 11 through which screws may be passed in mounting the butt in connection with a support. At one end of the butt is a curved semi-circular hood portion 12 terminating at its free end in a stop wall 13, and said hood including side wall members 14 formed integrally with and as a unit part of the hood portion 12 and shank 10, said walls having rounded outer edges 15 which gradually taper into the attaching plate as indicated by the curved portion 16. Said side walls 14 have oppositely disposed apertures 17 to receive the pintle pin of the hinge which also passes through a knuckle on the other butt of the hinge, not shown, which operates

within the chamber formed between the side walls 14 and the hood 12.

In forming a pair of hinge butts shown in Figs. 1 and 2 of the drawings, I employ a blank 18 substantially similar to that outlined in Fig. 3 of the drawings, the relatively straight end portions 10a of the blank forming the attaching plates 10 of the separate butts, the adjacent portions 12a forming the hoods 12 of said butts, the latter being joined by an intermediate section 19. Disposed at opposite sides of the parts 12a of the blank are outwardly extending rounded portions 14a from which the side walls 14 of the butts are formed.

After properly laying out the blank 18, the next step in the operation of forming a pair of hinge butts consists in placing the blank within and between two dies 20—21. In the present instance, the die 20 constitutes the male member and the die 21 the female member. The die member 20 has a punch end 20a, two side walls 20b of which are beveled in the manner seen in Fig. 4 of the drawings, whereas the other side walls are also beveled as seen at 20c, note Fig. 5, the latter walls terminating in rounded portions 20d. The die member 21 has a recess 21a formed therein to receive the blank and the punch 20a, two side walls 21b being tapered to correspond with the taper of the walls 20b, whereas other side walls 21c are tapered to correspond with the taper 20c, it being further noted that the corner edges 20e of the punch 20a are rounded as are also the edges 21e of the die member 21, so as to partially form the curvature of the hoods 12 from the portions 12a of the blank in the manner indicated in dotted lines in Figs. 4 and 5 of the drawings.

In the first forming operation of the blank, it will be seen that the sections 14a are turned upwardly as indicated in Figs. 4 and 5 of the drawings, and said sections are arranged at a slight inclination to the vertical plane. In other words, said sections are not disposed at right angles to the transverse plane of the blank as in the finished hinge butt. It will also be noted in this forming operation that the flow of the metal is distributed by virtue of the exertion of equal pressures upon opposite sides of the central portion of the blank, and thus the tendency of creeping of the workpiece or blank is obviated.

The female die member 21 also preferably includes an ejecting plug 22 so that the fashioned workpiece may be readily removed.

After the blank has been fashioned in the manner and by means of the dies as seen in Figs. 4 and 5 of the drawings, the same is placed in and between other dies 23 and 24, the latter being employed to finish and complete the formation of the pair of butt members, the die member 24 having oppositely disposed and upwardly projecting members 24a having rounded outer peripheral surfaces

to form the desired wall contour to the inner surface 12b of the hood 12, said projecting members 24a having relatively straight side walls 24b which taper sufficiently to release the workpiece or product from said die member. Intermediate the members 24a is a straight outer surface 24c which terminates at its ends in angularly disposed surfaces 24d so arranged as to form the desired angle to the free edge 13 of the hoods 12 of the respective butts. At opposite sides of each of the projecting members 24a, the upper edge of the die 24 is curved as seen at 24e and 24f to form the curvatures 15 and 16 in the edges of the side walls 14.

The die member 23 has oppositely disposed sockets 23a, the contour of one of which may be seen on an examination of Figs. 6 and 7 of the drawings and such as to form in conjunction with the contour of the members 24a the proper contour and formation of the hoods 12 of the respective pair of butts.

Disposed between the sockets 23a is a downwardly projecting member 23b adapted to operate upon the central portion 19 of the blank as formed from the dies shown in Figs. 4 and 5 of the drawings to depress said central portion in the formation of the hoods 12 and to leave a connecting fin 25 between the edges 13 of the hoods 12 of the pair of butts formed which is severed by a punch or in any other desired manner in separating said hood parts to form two complete and identical hinge butts similar to that shown in Figs. 1 and 2.

In the above operation it will be understood that the excess metal that may be contained in the portions 14a and which may be formed by the drawing operation of the portions 12a of the blank is firmly compressed into a single mass forming the end wall structures 14, which upon a consideration of Fig. 2 of the drawings will clearly appear to be of a thicker cross sectional form than that of the sheet metal from which the butt is formed and this variation and thickness might for example be as follows. If three sixteenths of an inch sheet metal were employed in the blank, the resulting thickness of the walls 14 might be one quarter inch greater or less in thickness. At the same time, it will be noted that the thickness of the hood portion 12 and especially the free end thereof is relatively thin. In this connection, it will be understood however that my invention is not necessarily limited to any variations in the thickness of the metal in the several parts of the butt nor to variations herein specifically set forth as this may be changed to suit any particular requirements in the resulting hinge butt.

It will also be understood that any slight flare of metal that may exist around the edges of the walls 14 may be removed after the

product has been removed from the dies 23 and 24 and in completing the formation of the butt, the hole 17 will be drilled or otherwise formed in the walls 14 to receive the pintle of the hinge.

In connection with the formation of the hinge butts, attention is directed to Fig. 8 of the drawings wherein a slight modification in the resulting product is shown which consists in including in conjunction with the side edges of the attaching plate 10 of the butt side flanges or walls 26 which extend onto and will be continuous with the side walls 14 of the hood 12 and to form a pair of butts of this character only a slight change is necessary in the formation of the separate die members 20—21, 23 and 24 to facilitate the formation of said side walls.

In forming either form of hinge butt disclosed, the successive operations may be performed under what is known as a cold forming process or without applying heat to the blank or workpiece. In other cases however, it will be desirable to heat the workpiece prior to its several operations and especially the forming operations performed by the dies 20, 21, 23 and 24. On the other hand, it will be apparent that the operation performed by the dies 20—21 may be conducted under the cold process after which the blank thus formed may be heated and the complete forming operation performed by the dies 23 and 24 may be conducted in accordance with the hot process. The several heating processes are preferably employed when the sheet metal from which each pair of hinge butts are formed is comparatively heavy.

It will be apparent that my invention is not limited to the specific manner or method of forming a blank which is provided prior to shaping the same into the resulting pair of hinge butts. These blanks may be formed in accordance with any of the known processes, and in referring to sheet metal, it will be understood that this term is descriptive of the general nature of the blank formed. In like manner, my invention is not limited to the specific structure of the hinge butt herein disclosed.

It will also be understood that various changes in and modifications of the specific structure of the hinge butt herein shown and described and the method herein set out for fashioning the same, may be made within the scope of the appended claims without departing from the spirit of my invention or sacrificing its advantages.

Having fully described my invention, what I claim as new and desire to secure by Letters Patent, is:—

1. The herein described method of making hinge butts having curved hood portions disposed at one end thereof which consists in forming a blank having relatively similar end portions, fashioning the blank to form of

the central portion thereof oppositely disposed curved hood members and extending shank portions with a connecting fin joining adjacent hood portions and severing said fin to form independent butt parts of similar size and contour.

2. The herein described method of making hinge butts having curved hood portions disposed at one end thereof which consists in forming a blank having relatively similar end portions, fashioning the blank to form of the central portion thereof oppositely disposed curved hood members and extending shank portions with a connecting fin, joining adjacent hood portions and severing said fin to form independent butt parts of similar size and contour, the hood portions of the respective butts including side wall members and forming pintle pin apertures in said side wall members.

3. The herein described method of fashioning a pair of hinge butts of similar shape and size and having curved hood portions at one end thereof, from a single sheet metal blank, which consists in first fashioning said blank to extend the ends thereof angularly with respect to the central portion and to arrange side edges of the central portion of the blank angularly with respect thereto to partially form the side walls of said hood portions, then fashioning the central portion of said blank to complete the formation of the hood portions of each butt in said pair joined by an intermediate connecting fin, and then removing said fin to form the independent butt parts.

4. The herein described method of fashioning a pair of hinge butts of similar shape and size and having curved hood portions at one end thereof, from a single sheet metal blank, which consists in first fashioning said blank to extend the ends thereof angularly with respect to the central portion and to arrange side edges of the central portion of the blank angularly with respect thereto to partially form the side walls of said hood portions, then fashioning the central portion of said blank to complete the formation of the hood portions of each butt in said pair joined by an intermediate connecting fin, then removing said fin to form the independent butt parts, and so fashioning the side walls of the hood portions of said butts as to increase the thickness of said walls with respect to the thickness of the metal employed in said blank.

5. The herein described method of fashioning a pair of hinge butts of similar shape and size and having curved hood portions at one end thereof, from a single sheet metal blank, which consists in first fashioning said blank to extend the ends thereof angularly with respect to the central portion and to arrange side edges of the central portion of the blank angularly with respect thereto to

partially form the side walls of said hood portions, then fashioning the central portion of said blank to complete the formation of the hood portions of each butt in said pair 5 joined by an intermediate connecting fin, then removing said fin to form the independent butt parts, and so fashioning the side walls of the hood portions of said butts as to increase the thickness of said walls with 10 respect to the thickness of the metal employed in said blank, and fashioning the curved outer walls of the hoods of said butts so as to reduce the thickness thereof.

6. The herein described method of fashioning 15 a pair of hinge butts of similar shape and size and having curved hood portions at one end thereof, from a single sheet metal blank, which consists in first fashioning said blank to extend the ends thereof angularly 20 with respect to the central portion and to arrange side edges of the central portion of the blank angularly with respect thereto to partially form the side walls of said hood portions, then fashioning the central portion 25 of said blank to complete the formation of the hood portions of each butt in said pair joined by an intermediate connecting fin, then removing said fin to form the independent butt parts, and so fashioning the side 30 walls of the hood portions of said butts as to increase the thickness of said walls with respect to the thickness of the metal employed in said blank, fashioning the curved outer walls of the hoods of said butts so as to reduce the thickness thereof, and forming pintle 35 pin apertures in the side walls of said hood portions.

7. The herein described method of fashioning 40 a pair of hinge butts of similar shape and size and having curved hood portions at one end thereof, from a single blank, which consists in providing a blank of predetermined contour, shaping the central portion of the blank to form adjacent hood portions joined 45 by a connecting fin, and removing said fin to form independent butt parts having hood portions disposed at one end thereof.

8. The herein described method of making 50 in one series of operations, a pair of similar hinge butts having curved hood portions disposed at one end thereof, from a single blank, which consists in providing a blank of predetermined contour, forming said blank to angularly dispose the side walls and ends with 55 respect to the central portion thereof, then shaping the central portion of the blank thus fashioned to form two hood portions having extending, attaching plates, said hood portions being joined by a connecting member, and then severing said member to form independent, butt parts.

9. The herein described method of making 60 in one series of operations, a pair of similar hinge butts having curved hood portions disposed at one end thereof, from a single blank,

which consists in providing a blank of predetermined contour, forming said blank to angularly dispose the side walls and ends with respect to the central portion thereof, then shaping the central portion of the blank thus fashioned to form two hood portions having extending, attaching plates, said hood portions being joined by a connecting member, and then severing said member to form independent butt parts, the hood portions of said 70 butt parts including side wall members and forming pintle pin apertures in said wall members.

10. The herein described method of making 75 pairs of hinge butts from elongated strip material in a series of operations, which consists in fashioning one section of said material in such manner as to form adjacent hood portions having extending, attaching plate portions, said hood portions being joined by 80 a short, connecting member, and then severing said connecting member to form independent butt parts, each having a hood portion at one end thereof.

11. The herein described method of making 85 hinge butts of the class specified, which consists in providing a sheet metal blank having oppositely disposed projecting members lying in the plane of the blank and arranged on one section thereof, upsetting said 90 section and projecting members only of the blank to form a curved hood portion having side wall members, said side wall members being formed by compiling the material of 95 said sheet metal projecting members and section to form said side wall members of a thickness greater than the thickness of the material employed in said blank, and then trimming the product thus formed to a finished size.

12. The herein described method of making 100 hinge butts of the class specified, which consists in providing an elongated sheet metal blank having pairs of oppositely disposed projecting portions on predetermined sections thereof, upsetting each section and pair of projecting portions only of the blank to form thereof curved hood portions having side wall members, said side wall members being formed by compiling the material of 105 said sheet metal projecting portions and section to form said side wall members of a thickness greater than the thickness of the material employed in said blank, and trimming the blank thus formed to produce independent hinge butts having curved hood portions disposed at one end thereof.

13. The herein described method of making 110 hinge butts of the class specified which consists in providing an elongated sheet metal blank having pairs of projecting portions on predetermined sections thereof, partially upsetting each section and pair of projecting portions only of the blank to form 115 thereof curved portions including side walls 120

formed from said sheet metal projecting portions and disposed angularly with respect to the plane of the blank, then heating the blank thus formed, then completing the upsetting of the curved portions and side walls, said side walls being formed by compiling the material of said projecting members and sections to form side walls of a thickness greater than the thickness of the material employed in said blank, and then trimming the blank to form independent butt members having hood portions disposed at one end thereof.

In testimony that I claim the foregoing as my invention I have signed my name this 20th day of December, 1929.

JOSEPH SOSS.
